CROSS FEED MECHANISM FOR LATHES

Alexander G. Whitehead, East Hartford, Conn.,
assignor to Niles-Bement-Pond Company,
Hartford, Conn., a corporation of New Jersey

Application June 8, 1937, Serial No. 147,078

6 Claims. (Cl. 82—24)

This invention relates to improved operating means for the tool supporting cross slide on the carriage of an engine lathe or other type of machine tool.

5 An object of the present invention is to provide improved means for adjusting the position of the cross slide so that the cross slide may be adjusted manually to different predetermined limited positions and so that adjustment of the cross slide 10 may be limited in one direction to a specific limited position; also by rotation of a frictionally held supplementary member carrying an abutment the cross slide may be, by the application 15 of additional pressure, moved to other advanced positions.

Another object of the invention is to provide an improved and convenient form of setting device to adjust the position to which the cross slide may be repeatedly moved in one direction.

20 And finally it is an object to provide a micrometer adjustment to permit movement of the cross slide to successive limited positions closely adjacent each other.

With the above and other objects in view the 25 invention includes the features of construction and operation set forth in the following specification and illustrated in the accompanying drawings.

In the accompanying drawings annexed hereto 30 and forming a part of this specification, I have shown the invention embodied in a standard form of tool room lathe but it will be understood that the invention can be otherwise embodied and that the drawings are not to be construed as 35 defining or limiting the scope of the invention, the claims appended to this specification being relied upon for that purpose.

In the drawings:

Figure 1 is a fragmentary transverse view of a 40 portion of an engine lathe showing one form of the improved cross slide and adjusting means therefor, parts being shown in section to more clearly indicate their construction.

Fig. 2 is a vertical sectional view taken upon 45 the plane of line 2—2 of Fig. 4 and showing the cross feed setting device.

Fig. 3 is a plan view of a portion of the cross feed adjusting mechanism shown in Fig. 2, and

Fig. 4 is a vertical sectional view taken upon 50 the plane of line 4—4 of Fig. 2.

In the above mentioned drawings there has been shown but one embodiment of the invention which is now deemed preferable, but it is to be understood that changes and modifications 55 may be made within the scope of the appended

claims without departing from the spirit of the invention.

Briefly, and in its preferred aspect, the invention may include the following principal parts: First, a cross slide movable on the carriage of a lathe or other machine tool; second, a screw rotatably mounted in the carriage and engaging a nut on the cross slide; third, rotating means supported on the carriage for said screw; fourth, a bracket on the machine tool rotatably supporting the 10 screw and controlling its endwise movement during movement of the carriage; fifth, a pinion on the rotating means for the screw; sixth, a gear rotated by said pinion; seventh, an abutment to limit the rotative movement of the gear; and 15 eighth, adjustable frictional means to vary the adjustment of the abutment.

Referring more in detail to the figures of the drawings and referring first to Fig. 1, there is shown in outline a portion of a lathe bed 10 on 20 which a carriage 11 is mounted. For supporting the carriage 11 for longitudinal movement along the bed or base 10 guideways 12 may be provided of the usual or conventional form.

Adapted to slide upon suitable ways formed in 25 this carriage 11 in a direction normal to the direction of movement of the carriage along the base 10 is a cross slide 13. Preferably and as shown, there is a supplemental or compound tool slide 14 angularly adjustable and slidably 30 mounted upon the cross slide 13. This latter slide 14, however, is of usual or conventional construction and forms no part of the present invention. In the slide 14 may be mounted the usual tool post 15 having a cutting tool 16 therein. 35

In order to adjust the position of the cross slide 13 relative to the carriage 11 there is provided a cross slide screw 17 mounted within the carriage 11 and disposed in a direction normal to the guideways 12 upon which the carriage 11 is 40 slideable. At the rear end of this cross slide screw 17 there is a suitable head or sleeve 18, preferably housing an anti-friction bearing 19, the outer race of which is fixedly retained within the sleeve and the inner race of which is secured directly to the rear end of the cross slide screw 14. 45

As the cross slide 13 may be used for turning conical as well as cylindrical surfaces upon work pieces, the head 18 within which the end of screw 17 is enclosed is slidably mounted within a suitable bracket 20 secured in the rear surface of the carriage 11 and has a depending portion 21 adapted to engage within the slide 22 of a taper attachment angularly adjustable in the usual manner from brackets or other supports secured 50 55

directly to the rear face of the lathe bed 10. By adjusting the angular position of the taper slide 22 movements of the carriage 11 along the bed 10 will force the sleeve 18 or head carrying the screw 17 to move toward the left or right and carrying with it the cross slide 13, thus varying the lateral position of the slide 14 on which the tool 16 is mounted.

When it is desired to use the mechanism for 10 cylindrical work pieces the head or sleeve 18 carrying the screw 17 may be clamped in position by a clamping screw 23 shown in section in Fig. 1. Also during operation upon cylindrical work the taper slide 22 may be removed or adjusted to 15 a position parallel to the ways 12. In operating either upon taper or cylindrical work pieces the screw 17 must be initially rotated to preliminarily adjust the position of the cross slide 13 and the tool 16. For this purpose the following 20 mechanism has been provided and is shown most clearly in Fig. 2. The cross slide screw 17 has its intermediate portion formed with screw threads and immediately rearward of that threaded portion engages within the sleeve 18 carrying the bearing 19 at its rear end. The forward portion of the screw 17 is reduced in diameter and longitudinally splined as shown at 24, there preferably being four or six axially disposed splines provided in this end of the screw.

30 Suitably supported in the forward portion of the carriage 11, preferably in a bracket 25 suitably secured to the front face of the carriage, is a sleeve 26, the intermediate portion of which is provided with gear teeth 27 forming a pinion. 35 The sleeve 26 is provided with a splined hole slidably engaging the splines 24 on the forward end of the cross slide screw 17. Also mounted on this sleeve 26 is a hand wheel 29 preferably keyed directly to the sleeve and having a nut 28 threaded on the sleeve 26 engaging its front face. 40 By rotating this hand wheel 29 and the sleeve 26 carried thereby the cross slide screw 17 will be rotated and will advance a nut 30 on the lower surface of slide 13 and threaded upon its intermediate section in either direction. By means of 45 a suitable screw 31 or other fastening means this lead nut 30 is directly attached to the slide 13 in fixed position.

It is desirable in repetition work to provide 50 means for rapidly withdrawing the tool 16 from engagement with a work piece and being able to again position the tool at precisely the same diameter. For this purpose there is provided a large gear 32 meshing with gear teeth 27 on the sleeve 26 above referred to. Whenever the hand wheel 29 and sleeve 26 are rotated to rotate the cross slide screw 17 this second gear 32 is simultaneously rotated but at a much slower rate. This second gear 32 is rotatably mounted upon 55 the hub of a member 33 mounted in the bracket 25 presently to be more fully described.

In the gear 32 is an angular recess 34 extending completely around one face of this gear. In one position there is inserted a stud 35 which forms 60 an abutment directly across this recess and therefore limits the length of the recess to less than a complete circle. On the member 33 rotatably supporting this second gear 32 is a stud 36 outstanding therefrom and entering the annular 65 groove 34 in the gear 32. It will be seen from the above that by rotation of the hand wheel 29 and sleeve 26 the abutment 35 in the annular groove 34 will be rotated and will be moved against one or the other side of the stud 36. With the member 33 carrying the stud 36 clamped in position

but limited movement can be effected in either direction of the cross slide 13 by means of the sleeve 26 and hand wheel 29.

In order to provide means to clamp the member 33 carrying the stud 36 in adjusted angular 5 position, the member 33 and the gear 32 may be mounted upon a central stud 37 having a large head at one end and passing through the bracket 25 for the sleeve 26. Stud 37 has a threaded member or nut 38 on its rear threaded 10 end. This threaded member 38 or nut may have a forwardly extending handle 39 formed thereon enabling it to be manually rotated to force the stud 37 rearwardly to clamp its head portion against the front face of the sleeve for member 15 33 and bind the member 33 against a surface of the bracket 25. The gear 32 is freely rotatable upon the sleeve of member 33 when this member is clamped in adjusted positions. To prevent rotation of the stud 37 when the threaded member 20 or nut 38 is moved from clamping to unclamping position, a key 40 may be inserted engaging a key-way within the bracket 25. To retain a slight resistance against oscillation of this member 33 when the nut 38 has been moved 25 to its releasing position several light springs 41 may be interposed between the fixed bracket 25 and a washer on stud 37 adjacent the nut 38 and the clamping head of member 33. The force with which stud 37 clamps member 33 in position 30 may be widely varied by varying the pressure applied manually with which nut 39 is tightened on the threads of stud 37.

To facilitate adjustments of the cross slide 13 of predetermined small amounts, the hand wheel 35 29 is provided with a graduated sleeve or ring 42 surrounding a cylindrical surface thereof and directly adjacent a surface of a cover plate 43 secured to the bracket 25. On this surface is a zero or reference line 44. It will readily be seen, 40 therefore, that by means of these graduations the angular movement imparted to the hand wheel 29 and the cross slide screw 17 may be determined. To set this graduated dial 42 so that its zero may be in alignment with the fixed reference 45 line 44 in any position of the cross slide 13, a screw 45 may be provided within the hand wheel 29 having a conical portion thereon. Rotation of the screw 45 in one or the other direction will raise or lower a short pin 46 bearing upon the 50 conical surface of the screw at one end and frictionally engaging against the inner cylindrical surface of the graduated sleeve 42 at its outer end.

In operation the hand wheel 29 is rotated with 55 the nut 38 loosened to position the slide 13 to any position called for by the particular operation being performed. In this loosened position of the nut 38 the gear 32 and member 33 will freely rotate together. When the tool 16 has been adjusted accurately to a predetermined position the nut 38 is tightened with the stud 35 interrupting the arcuate groove 34 in contact with a side of abutment or stud 36. These studs are in contact when the cross slide 13 is moved in one direction by rotation of the hand wheel 29 far enough to cause rotation of the stud 36. The hand wheel 29 and sleeve 26 may then be rotated in the opposite direction to withdraw the tool 16 from adjusted position until stud 35 takes up 60 65 70 75 80 85 90 95 100 105 110 115 120 125 130 To move the tool 16 to a new advanced position the nut 38 is not tightly clamped but moved to a position frictionally retaining the member 33 in position but permitting rotation by forcing the hand wheel 29 to rotate the sleeve 26, the gear 32, and member 33 against this added friction. The distance moved by this rotation of the member 33 to a new position may be indicated by the graduations of the dial 42.

10 On the bracket 25 secured to the carriage 11 there may be provided the usual latch lever 50 movable into and out of engagement with a rod 51. This rod 51 may be attached in any manner (not shown) to the cross slide 13 so that it will move axially with movements of the cross slide. By placing nuts 52 on the rod 51 adjustable axially to different positions and with the latch 50 in engaging position, movement of the cross slide may be stopped at predetermined limiting positions.

20 What I claim is:

1. A cross slide mechanism for lathes comprising in combination, a carriage, a slide movable thereon, a screw rotatably mounted in said carriage engaging a nut on said slide, a member having a hand wheel thereon mounted for rotation with said screw whereby said slide may be moved by rotation of said member, a pinion on said member meshing with a gear rotatably mounted in said carriage, an arcuate slot formed in said gear, an abutment engaging said arcuate slot, frictional means to retain said abutment in position, and manual means to vary said frictional means.

35 2. A cross slide mechanism for lathes comprising in combination, a carriage, a slide movable thereon, a screw rotatably mounted in said carriage and engaging a nut on said slide, a member having a hand wheel thereon mounted for rotation with said screw whereby said slide may be moved by rotation of said member, a pinion on said member meshing with a gear rotatably mounted in said carriage, an arcuate slot formed in said gear, an abutment engaging said arcuate slot, means to adjust said abutment to engage against an end of said slot in different angular positions, frictional means to retain said abutment in adjusted position, and manual means to vary said frictional means.

40 3. A cross slide mechanism for lathes comprising in combination, a carriage, a slide movable thereon, a screw rotatably mounted in said carriage and engaging a member on said slide, a member having a hand wheel thereon mounted for rotation with said screw whereby said slide may be moved by rotation of said member, a pinion on said member meshing with a gear rotatably mounted in said carriage, an arcuate slot formed in said gear, an abutment supported on said carriage and engaging against an end of said arcuate slot, frictional means to retain said abutment in position, and manual means to vary said frictional means.

45 carriage and engaging a member on said slide, a member having a hand wheel thereon mounted for rotation with said screw whereby said slide may be moved, a pinion on said member meshing with a gear rotatably mounted in said carriage, an arcuate slot formed in said gear, an abutment supported on said carriage and engaging against an end of said arcuate slot, frictional means to retain said abutment in position, and manual means to vary said frictional means.

50 4. A cross slide mechanism for lathes comprising in combination, a carriage, a slide movable thereon, a screw rotatably mounted in said carriage and engaging a nut on said slide, a sleeve having a hand wheel thereon splined to said screw for rotating said screw and moving said slide, a pinion on said sleeve, a large gear mounted in said carriage and meshing with said pinion, an arcuate slot formed in said gear, an abutment adapted to engage an end of said arcuate slot, frictional means to retain said abutment in position, and manual means to vary said frictional means.

55 5. A cross slide mechanism for lathes comprising in combination, a carriage, a slide movable thereon, a screw rotatably mounted in said carriage and engaging a nut on said slide, means to vary the axial position of said screw during movement of said carriage, a sleeve having a hand wheel thereon splined to said screw for rotating said screw and moving said slide, a pinion on said sleeve, a large gear mounted in said carriage and meshing with said pinion, an arcuate slot formed in said gear, an abutment engaging said arcuate slot, frictional means to retain said abutment in position, and manual means to vary said frictional means.

60 6. A cross slide mechanism for lathes comprising in combination, a carriage, a slide movable thereon, a screw rotatably mounted in said carriage and engaging a nut on said slide, a sleeve having a hand wheel thereon splined to said screw for rotating said screw and moving said slide, a pinion on said sleeve, a large gear mounted in said carriage and meshing with said pinion, an arcuate slot formed in said gear, an abutment supported on said carriage and engaging against an end of said arcuate slot, frictional means to retain said abutment in an adjusted position, and manual means to clamp and unclamp said frictional means.

ALEXANDER G. WHITEHEAD.
